UNITED STATES PATENT OFFICE.

RAYMOND D. SCHNOOR, OF CHICAGO, ILLINOIS.

MECHANICAL MOVEMENT.

Application filed July 28, 1923. Serial No. 654,335.

My invention has particular relation to operating means for operating the usual opposite shutters of skylights although not limited to this use alone.

The main object of the invention resides in the provision of simple and effective means whereby either of two reciprocal members may be positioned to either end of its movement while the other is at either end of its movement through the medium of a single operating member. As applied to the operation of opposite shutters of a skylight both shutters may be fully opened or closed or either may be fully opened or closed without necessitating the other being in any particular position such as closed position, thus providing a universal control of the opposite shutters through the medium of a single operating member, whereby where distant operation is necessary or convenient, as is usual in the control of skylight shutters, only one train of distant control mechanism is necessary.

With this object in view my invention consists in certain features of novelty in the construction, combination and arrangement of parts by which the said object and certain other objects hereinafter appearing are effected, all as fully described with reference to the accompanying drawings and more particularly pointed out in the claims.

In the said drawings—

Figure 1 is a fragmental top plan view of a skylight equipped with the mechanism of my invention for operating the opposite shutters of the skylight.

Figure 2 is a partial transverse section of the same.

Figure 3 is an enlarged section taken on the line 3—3 of Fig. 2.

Figure 4 is an enlarged horizontal section of one of the connecting rod ends hereinafter described.

Like characters of reference indicate like parts in the various views.

In the said drawings 1 designates generally a skylight structure of usual construction provided with a raised longitudinally extending central portion 2. The opposite vertical sides of this central portion are provided with openings and opposite sets of shutters 4 are pivotally mounted on the structure on horizontal longitudinally extending axes for closing respective openings 3, all as is usual. The shutters of each set are connected together by a usual link 5 whereby

they are operated as a unit, and it is usual to provide several units of opposite shutters in the length of the skylight, as shown in Figure 1, to close pairs of opposite openings 60 3 arranged longitudinally of the skylight.

Arranged at intervals along the central portion 2 of the skylight are transverse strut bars 6 which are disposed at the top of the vertical sides of the central portion 2. Vertical brackets 7, disposed intermediate the sides of the central portion 2, are secured to respective bars 6 and extend downwardly therefrom, and a central shaft 8, extending longitudinally of the skylight, is supported 70 for rotation in suitable apertures in the brackets 7 and in a bracket 9, secured to an end wall 11 of the skylight, see Fig. 1. A worm gear and depending endless chain device 12 of usual construction is associated 75 with the bracket 9 for manually rotating the shaft 8 from the floor of the building.

The several units of opposite shutters are operated in unison from the shaft 8 by means of duplicate mechanisms, and for this reason 80 but one of these mechanisms will be described.

A small spur gear 13 is secured to the shaft 8 adjacent a respective bracket 7, and a pair of large spur gears 14 of equal size are mounted for rotation on stud bearings 15 secured to the bracket 7 and mesh with the gear 13, the axes of the gears 14 being disposed in a common horizontal plane and in parallelism with the shaft 8. A pair of crank pins 90 16 of usual construction are mounted on respective gears 14 and are sequentially timed, in this case at 90°, for purposes hereinafter set forth.

A pair of brackets 17 are secured on the 95 respective bar 6 and are disposed on opposite sides of the respective bracket 7 adjacent respective of opposite sets of shutters of a pair thereof. A pair of arms 18 are pivotally mounted at 19 on respective brackets 17 on 100 axes parallel to the shaft 8 and extend downwardly from these brackets. A pair of links 21 are pivotally secured at their opposite ends to the lower ends of respective arms 18 and to respective links 5 whereby reciprocal movement of the arms will open and close respective sets of shutters 4, and the brackets 17 are provided with opposite stops 22 which limit the opposite, i. e., shutter opening and closing, movements of respective arms 18. The arms 18 are connected to 105 respective adjacent crank pins 16 by longi-

tudinally resilient connecting rods 23 which have their inner ends journaled on respective crank pins 16 and their outer ends pivotally connected to respective arms 18 intermediate the pivotal axes 19 and the lower ends thereof. The outer end of each connecting rod comprises a tubular portion 24 secured at one end to the main portion of the rod in alignment therewith by means of a head 25 at the 10 adjacent end of the rod, a plug 26 screw-threaded into the portion 24 at the outer end thereof, a cylindrical block 27 disposed within the portion 24 for longitudinal sliding movement, and two coiled compression 15 springs 28 disposed within the portion 24 at respective ends of the block 27 and respectively abutting the head 25 and plug 26 and abutting the block whereby to resiliently maintain the block in its normal position 20 at an intermediate point in its movement within the portion 24. See Fig. 4. The block 27 is pivotally secured to the respective arm 18 by a headed stud 29 passing through diametrically opposite longitudinally extending 25 slots 31 in the tubular portion 24 and a diametrical bore in the block 27 for pivotal movement therein and screwthreaded into the respective arm 18.

The arms 18 are moved between the stops 30 22 by angular movement of the respective gears 14 by means of the crank pins 16 and connecting rods 23 whereby the respective shutters are opened and closed. The throws of the crank pins 16 are excessive so that the 35 arms 18 engage the stops 22 at both ends of their movements before the crank pins reach the lines intercepting the axes of respective gears and the axes of respective studs 29. In this case the arms 18 engage respective stops when there is still 45° of angular distance between the respective crank pins and the respective lines. The springs 28 permitting the block 27 to move in the tubular portion 27 of the connecting rods 23 provide for the additional movement of the crank pins so that in the cycle of each gear 14 the stroking of the respective arm 18 is alternated with 40 periods during which the arm 18 is held against respective stops 22, during one period the arm 18 being held in closed shutter position and during the other period it being held in open shutter position. As shown these periods each embrace 90° in the angular movement of respective gears 14.

55 As hereinbefore stated the crank pins 16 are sequentially timed at 90° so that the stroking periods of each arm occur during the periods when the other arm is held against one of the respective stops whereby either arm may be positioned to either end of its movement while the other arm is positioned at either end of its movement. The result is that either of the opposite sets of shutters may be positioned in open or closed position 60 65 while the other is positioned in either open

or closed position thus providing universal adjustment thereof. The gears 14 are as is obvious operated by the shaft 8 through the small gear 13 whereby the universal control of the shutters is provided through a single 70 train of mechanism. It will be further observed that the mechanism permits of a plurality of shutter operating mechanisms being disposed at points along the operating shaft 8 and operated in unison therefrom. 75

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following. 80

Claims:

1. A device of the character described including two reciprocable members, a revolvable operating member, and means whereby either of said reciprocable members may be positioned at either end of its stroke while the other reciprocable member is at either end of its stroke by angular adjustment of the operating member including two crank pins operated therefrom and connected with respective reciprocable members for controlling the stroking thereof and timed to act sequentially thereon. 95

2. A device of the character described including two reciprocable members, a small gear, and means whereby either of said reciprocable members may be positioned at either end of its stroke while the other reciprocable member is at either end of its stroke by angular adjustment of said small gear including two large gears equal in size and meshing with said small gear and two crank pins controlling the stroking of respective reciprocable members and mounted on respective of said large gears and timed to operate sequentially as the gears rotate. 110

3. A device of the character described including two reciprocable members, stops limiting the strokes of said members in both directions, a revolvable member, a pair of crank pins operated from the revolvable member in sequentially timed relation, and resilient connections between the crank pins and respective reciprocable members for stroking the reciprocable members, the throws of said crank pins being excessive whereby said resilient connections cooperate with the sequentially timed operation of the crank pins to effect the stroking of either reciprocable member to either end of its movement while the other reciprocable member is positioned at either end of its movement by movement of said revolvable member. 115 120 125

4. A device of the character described including two pivoted arms, stops limiting the movement of said arms in both directions, a 130

small revolute gear, a pair of large revolute gears equal in size and meshing with said small gear, two crank pins mounted on respective large gears, two longitudinally resilient connecting rods connecting respective crank pins and arms, said crank pins being sequentially timed and the throws thereof being excessive whereby to cooperate with the resilient connecting rods to effect the stroking of either arm to either end of its movement while the other arm is positioned at either end of its movement by rotation of said small gear.

5. A device of the character described including two spaced pivoted arms having their pivotal axes disposed in parallelism, stops limiting the movement of said arms in both directions, a revolute shaft disposed

intermediate the arms and parallel to the pivotal axes of the arms, a small spur gear 20 secured to the shaft, a pair of large revolute gears of equal size disposed in parallelism with the shaft and meshing with the small gear, two crank pins mounted on respective large gears, two longitudinally resilient connecting rods connecting respective crank pins and arms, said crank pins being sequentially timed at 90° and the throws thereof being excessive whereby to cooperate with the resilient connecting rods to effect the stroking 30 of either arm to either end of its movement while the other arm is positioned at either end of its movement by rotation of said shaft.

In witness whereof I hereunto affix my signature this twenty-fourth day of July, 1923.

RAYMOND D. SCHNOOR.
